UNITED STATES PATENT OFFICE.

EDGAR GOOD, OF TOLEDO, OHIO, ASSIGNOR TO THE UNITED STATES MALLEABLE IRON COMPANY, OF TOLEDO, OHIO, A CORPORATION OF OHIO.

RAIL-CLAMP.

949,321.

Specification of Letters Patent. Patented Feb. 15, 1910.

Application filed May 15, 1909. Serial No. 496,304.

To all whom it may concern:

Be it known that I, EDGAR Good, a citizen of the United States of America, residing at Toledo, in the county of Lucas and State of Ohio, have invented certain new and useful Improvements in Rail-Clamps, of which the following is a specification, reference being had therein to the accompanying drawings.

30 It is the object of the invention to obtain a construction of rail clamp which is applicable to the standard constructions of rail joints, and which, when applied, will securely hold the end portions of the rail from 35 relative movement.

It is a further object to obtain a simple and inexpensive construction.

The invention therefore consists in the construction as hereinafter set forth.

20 In the drawings—Figure 1 is a side elevation of a rail joint to which my improvement is applied; Fig. 2 is a cross section on line ---x , Fig. 1; Fig. 3 is a broken end view showing a modified construction, 25 and Fig. 4 is a perspective view of one of the clamping plates.

The standard construction of rail joints is one in which the adjoining end portions of the rails—such as A A', are clamped together by fish plates B B' secured by clamping bolts C. It is also usual to provide these fish plates with bottom flanges D which extend over the base portion E of the rail. 30 My improved clamp is applicable to such a joint without the necessity of removing the fish plates, and is constructed as follows: F and F' are two members arranged upon opposite sides of the rail and each provided with a hooked flange or jaw G for engaging 35 the flanges D of the fish plates and the base E of the rail. These members F F' are further provided with inwardly-projecting portions H H' which extend into proximity to each other at substantially the center 40 of the base of the rail. The portions H H' are provided with grooved channels for receiving a wedge member or key I which extends transversely beneath the joint between the rails. The sections F F' are still 45 further provided with downward projections J J', which are spaced from each other by means of integral inwardly-extending and abutting lugs K K'—illustrated in Fig. 50 3—or preferably by the spacer L—shown in Fig. 2—the opposite ends of which are

recessed to engage lugs M M' on the portions J J'. This latter construction permits of applying the device to various widths of rail by merely exchanging the spacer for one of different length. The 60 members F F' are clamped to each other by transversely-extending clamping bolts N N', and the wedge or key member I is clamped by a bolt O, which extends at an angle to the longitudinal axis of the wedge, and engages apertures in the wedge and the member F'. The head of the bolt preferably engages a recess in the large end of the wedge, while the threaded end of the bolt projects outward beyond the side of the member F' 70 and is engaged by a clamping nut P.

With the construction as described, to apply the clamp to the rail joint, it is merely necessary to place the members F F' upon opposite sides of the rail with the spacer L 75 therebetween, and then insert and secure the bolts N N'. After this, the wedge I, which is in its grooved seat in the portions H H', may be tightened by the insertion of the bolt O and the drawing up of the bolt 80 by the nut P. This clamping will force the upper face of the wedge against the adjacent end portions of the rails, the force reacting against the hooked portions G on the members F F'. Thus sufficient pressure 85 may be brought to bear to absolutely hold the rail sections from relative movement.

My construction has the advantage that, while the rails are held at all times with their abutting ends at precisely the same 90 height, freedom is still provided for the rails to expand or contract. The vibration and pressure of a load on top of the rails will be distributed over the entire surface of the wedge which comes in contact with the entire width of the rail at the under side of the rail foot. Tipping or turning of the rail is prevented by the engagement of the hooks or jaws with the rail base in connection with the clamping action of the wedge, 95 and the engagement of said jaws with the flanges of the fish plates, which prevents the latter from becoming loose.

What I claim as my invention is:

1. The combination with adjoining rail 105 sections, of a pair of members upon opposite sides of said rail sections having chair bearings extending inward beneath the rail base and downward projections, a strut for spacing said downward projections, a clamping 110

bolt between said strut and the rail base, and a wedge seated on said chair bearings and engaging the bottom face of the adjoining rail sections.

5 2. The combination with adjoining rail sections, of a pair of members upon opposite sides of said rail sections provided with chair bearings extending inward beneath the rail base and downward projections, a 10 strut for spacing said downward projections, a clamping bolt between said strut and the rail base, a wedge seated on said chair bearings, and a bolt for adjusting said wedge to clamp the same against the bottom faces of 15 the adjoining rail sections.

3. The combination with adjoining rail sections, of a pair of clamping plates upon opposite sides of said rail sections and having chair bearings extending beneath the 20 rail base, a wedge seated on said chair bearings and bearing against the bottom faces of the adjoining rail sections, and a bolt extending at an angle to the axis of the wedge for clamping the latter against the 25 rail.

4. The combination with adjoining rail sections, of a pair of members arranged upon opposite sides of said rail sections,

having grooved chair bearings extending beneath the rail base, a wedge seated in said 30 grooved bearings and bearing against the under face of the adjoining rail sections, a bolt engaging the head of said wedge and extending at an angle to the axis thereof through an aperture in the opposite side 35 member, and a nut for clamping said bolt.

5. The combination with adjoining rail sections, fish plates upon opposite sides of said rail sections, having flanges extending over the base of the rail, a pair of members upon 40 opposite sides of said rail sections, jaws for engaging the flanges of said fish plates, chair bearings extending beneath the base of the rail and downward projections, a strut for spacing said downward projections, a clamping bolt between said strut and the base of the rail, a wedge engaging said chair bearings and bearing on the under face of the adjoining rail sections, and adjusting means 45 for said wedge to clamp the rail. 50

In testimony whereof I affix my signature in presence of two witnesses.

EDGAR GOOD.
